UNITED STATES PATENT OFFICE.

PETER HOME, OF BESSEMER, MICHIGAN.

MINER'S LAMP.

SPECIFICATION forming part of Letters Patent No. 623,370, dated April 18, 1899.

Application filed December 9, 1898. Serial No. 698,750. (No model.)

To all whom it may concern:

Be it known that I, PETER HOME, a citizen of the United States, residing at the city of Bessemer, in the county of Gogebic and State of Michigan, have invented certain new and useful Improvements in Miners' Lamps; and I do hereby declare the following to be a full, clear, and exact description of the invention, such as will enable others skilled in the art to which it appertains to make and use the same.

My invention consists in the novel features hereinafter described, reference being had to the accompanying drawings, which illustrate my invention, and the said invention is fully disclosed in the following description and claims.

Referring to the said drawings, Figure 1 represents a perspective view of a miner's lamp embodying my invention. Fig. 2 is a plan view, partly in section, of the holder for the lamp-body. Fig. 3 is a vertical sectional view of the lower part of the lamp-body and the encircling portion of the holder.

In the drawings, A represents the lamp-body, which is provided with a wick-holding tube a and a cover a'. The lower part of the lamp-body is formed with a projecting bead a², as is usual in the construction of miners' lamps.

a³ represents a hanger or auxiliary supporting devices secured to the lamp-body, extending above the same and having a pointed end bent downwardly to enable the lamp to be hung from a suitable support.

B represents the lamp-support, which consists, preferably, of a single piece of metal.

b represents the shank, which is pointed at one end and is provided at the other end with an annular holder formed by bending the material of which the shank is made outwardly at b', then nearly in the form of a circle, as at b², to the point b³, and thence outwardly, forming a short arm b⁴. The curved portion or annular holder b² is grooved on its inner side, as shown at b⁵, to receive the bead a² on the bottom of the lamp-body. (See Fig. 3.) The curved portion b² possesses a certain amount of resilience, which keeps

the bend b³ and arm b⁴ away from the bend b' normally, and I provide a retaining device to hold the said parts together and retain the bead of the lamp-body within the groove b⁵. In this instance I have shown a hook C, having a portion c bent around the head of the shank adjacent to the bend b' and held in place by an annular rib or flange b⁶, formed on the shank. It is obvious that I may use other forms of retaining device for this purpose.

When the holding device is attached to the lamp, the bead a² of the lamp-body is placed within the groove b⁵ of the curved portion b², and the arm b⁴ is pressed toward the head of the shank, so as to hold the bead of the lamp-body within it. The hook C is then dropped over the bend b³, as shown in Fig. 1, and the parts will be held securely together, but will permit the lamp-body to be turned around to any desired position within the annular holder.

The pointed end of the shank can be stuck into a joist or the side of a tunnel or shaft and will support the lamp in any desired position.

While I do not wish to be limited to a holder made from one piece, it is a very desirable construction on account of the cheapness with which it can be manufactured.

What I claim, and desire to secure by Letters Patent, is—

1. A holder for miners' lamps comprising a shank pointed at one end and provided at the other end with an annular portion grooved on its inner side to engage a bead on the lamp-body and a retaining device for securing said annular support around the lamp-body, substantially as described.

2. A holder for miners' lamps comprising a shank provided at one end with a curved portion forming an annular support, said curved portion being grooved on its inner side to engage a bead on the lamp-body, and a retaining device for securing the ends of said curved portion together, substantially as described.

3. A holder for miners' lamps comprising a shank, a curved portion secured thereto

forming an annular holder and terminating in an operating-arm, said curved portion being grooved on its inner side to receive a bead on the lamp-body, and a retaining-hook secured to said shank and engaging the opposite end of said curved portion, substantially as described.

In testimony whereof I affix my signature in the presence of two witnesses.

PETER HOME.
